SNOW PLOW HOUSING

Byron L. Ertsgaard, Riverside, Calif., and John A. Gale, Wayzata, Minn., assignors to Toro Manufacturing Corporation, Minneapolis, Minn., a corporation of Minnesota

Original design application Feb. 5, 1965, Ser. No. 83,697, now Patent No. 205,531, dated Aug. 16, 1966. Divided and this application June 6, 1966, Ser. No. 2,563

Term of patent 14 years

(Cl. D35—2)

Fig. 3

FIGURE 1 is a top plan view of a snow plow housing embodying our new design;

FIGURE 2 is a front perspective view thereof;

FIGURE 3 is a side elevational view thereof.

The broken line illustration of the snow plow handle and the associated engine housing portions are shown for illustrative purposes only.

This is a division of design application Ser. No. D. 83,697 filed Feb. 5, 1965, and now Patent Number D. 205,531.

We claim:

The ornamental design for a snow plow housing, substantially as shown and described.
